LADDER JACK
 Robert L. Sears, 2119 E. 9th St.,
 Des Moines, Iowa 50316
 Filed Jan. 3, 1966, Ser. No. 518,407
 9 Claims. (Cl. 248—238)

This invention relates to a ladder jack and in particular to a scaffold support device for a ladder.

This invention relates to a scaffold support device which may be readily attached and removed from a ladder as well as be moved to any point along the ladder as desired without removal of the device. As the scaffold support device is moved to different heights along the ladder a hook means engages the adjacent ladder rung. The pivotal movement permitted and the shape of the hook means is such that the guide frame on which it is carried may be moved independently of the outer ladder section or with the outer ladder without interference from the rungs of the back ladder section. Moreover the hook means are adapted to engage only the rungs of the outer ladder on which the guide frame is mounted regardless of their position between the top and bottom sides of the ladder section. As the hook means moves up the ladder it is ratcheted over the rungs until the desired height is reached and then it is permitted to drop back slightly whereby the hook means automatically engages the adjacent ladder rung. Furthermore, the center of gravity of the hook means is located such that the hook means will be pivoted downwardly towards the rungs regardless of the angle between the ladder and the adjacent upstanding supporting surface. A stop means is provided to limit the pivotal movement towards and away from the rungs of the ladder whereby the hook means cannot become engaged with the rungs of the bottom ladder or pivot too far outwardly to shift the center of gravity to the opposite side of a vertical plane through the axis of rotation for the hook means.

The guide frame is provided with side flanges which nest between the side rails of the outer ladder and thereby limit lateral movement of the scaffold support device. The scaffold support device may be mounted on either the front or back side of the ladder as may be required.

One of the frame members of the scaffold support device is telescopingly adjustable and includes a safety stop means which will prevent accidental disassembling of the scaffold support device.

It is emphasized that the scaffold support device of this invention does not in any way interfere with the use or operation of the conventional single unit ladder or extension-type ladder.

This invention consists in the construction, arrangements, and combination of the various parts of the device, whereby the purposes contemplated are attained as hereinafter more fully set forth, specifically pointed out in the claims, and illustrated in the accompanying drawings, in which:

FIG. 1 is a fragmentary perspective view of a ladder with the ladder jack mounted thereon;

FIG. 2 is an exploded view of the ladder jack;

FIG. 3 is a fragmentary side elevation view taken along line 3—3 in FIG. 2 showing in particular the extendable frame member;

FIG. 4 is a cross-sectional view taken along line 4—4 in FIG. 3;

FIG. 5 is a side elevation view of the jack device mounted on the opposite side of the ladder from its position as shown in FIG. 1;

FIG. 6 is a fragmentary cross-sectional view taken along line 6—6 in FIG. 7;

FIG. 7 is a fragmentary top plan view of the jack device mounted on extension ladders; and

2

FIG. 8 is a fragmentary cross-sectional view enlarged to show the various positions of ladder rungs and positions to which the hook means may be pivoted.

The ladder jack device of this invention is referred to generally in FIG. 1 by the reference numeral 10 and is shown mounted on a ladder 12 having extendable sections 14 and 16.

The ladder jack, as shown in FIG. 1 is mounted on the back side of the ladder 12 and includes basically three main components, a guide frame 18 and a pair of support frames 20 and 22. As seen in FIG. 1, the guide frame 18 is hooked to the ladder 16 and the support frame 20 is extendable. All of the three main components are pivotally interconnected to form a generally triangular shaped device.

The guide frame 18 is generally rectangular in shape having a pair of longitudinal L-shaped in cross-section side members 24 interconnected by transversely disposed end square in cross-section members 26 and 28. A leg 25 (FIG. 6) on each side member extends between the side rails of the ladder 14 to limit lateral movement of the guide frame 18. Each of the end members 26 and 28 are hollow to receive connecting pins 30 and 32. The side members 24 are spaced apart a distance substantially equal to the width of the ladder while the transversely extending members 26 and 28 have outwardly extending end portions 34 and 36 which extend outwardly of the side members 24 and the sides of the ladder 12.

Adjacent the end member 28, is a transversely extending rocker shaft 38 with its ends rotatably mounted in the side frame members 24. A pair of hook members 40 of plate material are rigidly connected to the rocker shaft 38 closely adjacent the side frame members 24 and a handle 42 is positioned between the hook members 40 for manually rotating the hook members 40 out of engagement with ladder rungs 44 as seen in FIG. 1.

Each of the hook members 40 as seen best in FIGS. 6 and 7 has a relatively long throat portion 45 with its free end rigidly connected to the rocker shaft 38 which is adapted to rotate relative to the side guide frame members 24. The inside edge 46 of the hook 40 is parallel to the outside edge for a substantial distance and then diverges therefrom to form a concave edge 48 which terminates in a concave edge 49 with a relatively smaller radius of curvature for matingly engaging the rungs 44 of the ladder section 14. The forward edge of the hook 40 is convex at 49A along its entire length. A small finger 49B bridges the edge surface of the hook 40 between the convex outer edge surface 49A and the inner concave edge 49.

Normally the weight of the hooks 40 is sufficient to cause them to pivot downwardly for engagement with the ladder rungs 44 but if desired a ballast element 49C may be added to the handle 42 to accelerate this movement.

The hooks 40 are limited in their pivotal movement in both directions by stop elements 49D on the side members 24 of the guide frame 18. The stop elements are positioned to prevent inward movement of the hooks beyond that illustrated in the innermost position in FIG. 8 thereby preventing engagement with the rungs of the bottom ladder 16. In this case the stop element 49D engages the top edge of the hook rearwardly of its pivotal axis and in limiting outward pivotal movement it engages the hook element forwardly of the pivotal axis. In the latter case the hook is prevented from pivoting so far out that the center of gravity is shifted to the opposite side of a vertical plane through the hooks pivotal axis.

When the ladder jack is mounted on the ladder 12 as shown in FIG. 5, the support frame 20 is oriented with a channel or yoke shaped end 50 extending downwardly wherein side plate flanges 52 are aligned to be connected by the pin 30 to the guide end frame member 26. The

channel-shaped end 50 includes a transversely extending base portion 54 having an extendable pair of L-shaped sections 56 and 58 connected at its center. The L-shaped sections 56 and 58 nest in each other and are locked together by a pin 60 extending through aligned openings 62. A pair of U-shaped guide elements 64 and 66 are rigidly secured to the outer surface of the member 58 to hold in mating engagement adjacent legs of the extendable members as seen in FIG. 4. The guide element 60 is placed at the very end of the extendable member 58. A stop element 70 is positioned between the legs of the member 56 and disposed along its length between the guide elements 64 and 66. Thereby, the extendable elements 56 and 58 may move in either direction until the stop element 70 engages one of the guide elements 64 or 66. Thus, if the pin 60 ever is accidentally removed, the extendable elements 56 and 58 will not separate or be completely contracted.

The support frame member 22 also has a channel-shaped end 72 (FIG. 2) with side plate flanges 74 and a base element 76. As seen in FIG. 5, the flange plate elements 74 are adapted to embrace the ladder 16 and be aligned with the opening through the end member 28 of the guide frame 18 for interconnection by the pin 32. As seen in FIG. 5, a second pin 78 is employed on the opposite side of the ladder 16 from the pin 32 thereby giving extra assurance that the jack device will not pivot outwardly from the ladder as viewed in FIG. 5. The ends of the support frame sections 20 and 22 opposite the channel ends 50 and 72 respectively, are pivotally interconnected at 80. Thus, a support surface is provided by the support frame section 22 for scaffolding material 82 as seen in FIG. 5.

As seen in FIG. 1, the jack device is mounted on the side of the ladder facing the vertical support surface such as a wall. Consequently, the extendable support frame section 20 is as shown, turned end for end relative to its position in FIG. 5 and rotated 180 degrees from its position in FIG. 2. The scaffolding material would of course be placed on the support frame section 22.

In operation it is thus seen that the guide frame 18 with the hooks 40 engaging the rungs 44 of the ladder 16 is always positioned on the outer side of the ladder whether the jack device is mounted on the inside of the ladder as seen in FIG. 1 or on the outside as shown in FIG. 5. In converting from one position to the other it is only necessary to remove the pins 30, 32 and 78. The pin 78 is not necessary in positioning the jack device on the inside of the ladder as seen in FIG. 1. Depending on the angle at which the ladder rests against a vertical wall or the like, the support frame 20 will be extended or contracted by moving the pin 60 to the appropriate aligned openings in the extendable sections 56 and 58. The adjustment is made to position the support frame 22 in a horizontal plane to receive the scaffolding material 82.

In moving the jack device up the ladder the hooks 40 ratchet over the rungs 44. It is seen from FIG. 8 that regardless of where the rungs are placed relative to the top and bottom sides of the ladder section as seen by rungs 44, 44A, 44B, 44C and 44D, the forward convex edge 49A of the hooks will contact and slide over the rungs around the finger 49B whereupon the selected rung will be nested in mating engagement with the concave edge 49. Where the rungs are placed close together such as rungs 44 and 44A, the top rung 44A may still engage the concave edge 49 because the long narrow throat portion 45 is spaced above the lower rung 44. When a rung engages the throat 45 will automatically guide the rung into the hook edge 49 as the guide frame is lowered. By employing the narrow finger 49B and placing the rung engaging edge 49 closely adjacent thereto, there is maximum clearance between the finger 49B and the rungs of the lower ladder section 16 even if they are located close to the top side of that ladder section.

When the jack device is to be lowered, the handle 42 is used and pivoted outwardly against the action of gravity tending to pivot it into engagement with the rungs of the ladder 14. This results in an important safety feature since if control of the jack device is lost it cannot drop to the ground because the hooks 40 will automatically pivot inwardly into engagement with the next lower rung 44.

Also safety is provided in the frames 20 and 22 as they cannot accidentally come apart when the telescoping adjustment is being made between members 56 and 58.

Some changes may be made in the construction and arrangement of my ladder jack without departing from the real spirit and purpose of my invention, and it is my intention to cover by my claims, any modified forms of structure or use of mechanical equivalents which may be reasonably included within their scope.

I claim:

1. In a ladder jack device, a guide frame adapted to detachably engage the rails of a ladder for longitudinal movement therewith, hook means on said guide frame for detachably engaging the rungs of a ladder that extend between said ladder rails, a first scaffold support frame pivotally secured to said guide frame and extending outwardly therefrom, a second scaffold support frame pivotally secured to said guide frame and extending outwardly therefrom, said first and second support frame pivotally and detachably secured together to form a horizontal scaffold support,

each of said support frames has a channel-shaped portion on one end, said channel-shaped portions adapted to receive a ladder, said guide frame being pivotally secured between the outer ends of the channel portions of said support frame, said guide frame being rectangular in shape with transverse end portions having an opening formed therethrough, and a detachable rod extending through the ends of said channel portions and the opening in the adjacent guide frame end portion.

2. The structure of claim 1 wherein one of said scaffold support frames includes and is formed by a pair of interconnected extendable members, a lock means for selectively locking said extendable members together at a predetermined length and a stop means to limit the extension of said members upon removal of said lock means.

3. The structure of claim 2 wherein one of said extendable members includes a pair of guide elements slidably engaging said other extendable member, said stop means is secured to said other extendable member and positioned between said guide elements, one of said guide elements adapted to engage said stop element when said one frame is fully extended and the other guide element engage said stop element when said one frame is fully contracted, said extendable members are L-shaped in transverse cross-section and disposed in nesting relationship, said guide elements being secured to the outer surface of said one member and having a U-shaped outer end portion matingly engaging a pair of adjacent leg portions.

4. The structure of claim 1 and one of said channel-shaped end portions has a second rod extending through the ends of said channel portion and adapted to be disposed on the opposite side of a ladder from the first mentioned adjacent rod.

5. The structure of claim 1 wherein the transverse end portions of said guide frame extend outwardly of each side of the side portions of said guide frame and are adapted to terminate outwardly of the longitudinal side edges of a ladder for engagement with the flanges of said channel end portions on said support frame members, the side portions of said guide frame being L-shaped in cross-section with one leg of each side portion adapted to engage the inner side of an adjacent ladder rail to limit lateral movement of said guide frame.

6. The structure of claim 1 and said guide frame has a pair of longitudinally extending side portions, and a rod rotatably extends between the opposite longitudinal side portions, said hook means including a pair of hook members rigidly secured to said rod adjacent and between the sides of said guide frame for pivotal movement into and out of engagement with the rungs of a ladder.

7. The structure of claim 6 wherein said hook members have a center of gravity which tends to pivot said hook members downwardly between said side portions when said guide frame is disposed with an angle of less than 90 degrees between the underside of said guide frame and the horizontal.

8. The structure of claim 7 and stop means is provided to limit the inward pivotal movement of said hook means from moving beyond the substantial thickness of an outer ladder section in an extendable ladder and limit the outer pivotal movement from shifting the center of gravity to the opposite side of a vertical plane through the axis of rotation for said hook means.

9. The structure of claim 8 wherein said members each have an elongated throat portion connected adjacent its free end to said rod, said throat portion having a substantially straight inner edge extending from said pivotal axis and merging into a first concave edge portion and

5

10

15

20

25

then into a second concave edge portion at the outer end of said hook, said second concave edge portion having a smaller radius of curvature relative to said first concave edge portion and adapted to matingly engage the rung of a ladder, said second concave edge portion forming one edge of a rounded narrow finger portion and a convex edge forming the opposite side of said finger portion, said convex edge portion adapted to contact the rung of a ladder and slide said hook over said rung, said convex edge tapering from its outer most end remote from said finger portion inwardly towards said axis of rotation of said hook portion.
